United States Patent Office.

A. S. KINNEAR, OF VOLGA, INDIANA.

Letters Patent No. 72,406, dated December 17, 1867.

IMPROVEMENT IN SCAFFOLDS.

The Schedule referred to in these Letters Patent and making part of the same.

TO ALL WHOM IT MAY CONCERN:

Be it known that I, A. S. KINNEAR, of Volga, in the county of Jefferson, and State of Indiana, have invented a new and useful Improvement in Scaffolds; and I do hereby declare that the following is a full, clear, and exact description thereof, which will enable those skilled in the art to make and use the same, reference being had to the accompanying drawings, forming part of this specification.

The nature of my invention consists in so constructing and arranging two or more triangular frames, so that they will rest against a vertical side of a building or other construction, being supported from below by beams, sliding upon each other in the direction of their lengths, and working through thimbles to prevent any side play, the upper bar being pivoted in the angle of the frame. The frames are provided with rollers on their vertical sides to lessen the friction. The horizontal sides act as supports for the flooring of the scaffold. By a system of cords and pulleys or sheaves, in connection with suitable gearing and cranks, the scaffold may be raised or lowered at pleasure by persons on it or on the ground.

I will now proceed to describe the construction and operation of my invention.

Figure 1 is a side elevation of the scaffold, showing it raised against a wall.

Figure 2 is a front elevation of the same.

Figure 3 is designed to show the ratchet and pawl in elevation.

Figure 4 is a sectional view on a smaller scale, designed to show an arrangement of the cords and pulleys by which the scaffold may be raised or lowered by persons on the scaffold and on the ground at the same time.

Similar letters of reference indicate corresponding parts.

A is the wall, B B are the vertical and horizontal sides of the frame, and C the diagonal braces. D D are metal plates, at the corners, to strengthen the frame, and also to act as a bearing for the pivot-bolt e. d d are rollers, let into the vertical side B. j j j are the planks, forming the flooring. E E are beams, which slide upon each other lengthwise, and are prevented from working laterally by the thimbles e e. The end of the beam, resting on the ground, is shod with metal, w, while the upper end of the other is strapped with metal, and hinges on the bolt e. a is the rope, which is fastened at f, passes down through grooves in the beams, around the sheave g, thence upward around the sheave k, which is attached to the beam by means of the thimble b, thence to the shaft y, which is suspended by hangers from the end of B. The spur-wheel h, on the end of the shaft y, meshes with the pinion above. The crank, m, is on the pinion-shaft. n o show the pawl and ratchet on the other end of the pinion-shaft.

In fig. 4 it will be seen that a pulley or sheave has been placed on the bolt e, and another at f, also a shaft, Z, on which is the crank x. t is a staple, under which the rope passes, and l is a knot or obstruction in the rope to prevent its passing under.

Operation.

Two or more scaffolds or supports are placed against the wall, as in fig. 1 and fig. 2. The flooring-boards are placed on as shown, and, if necessary, held in position by hook-bolts. If the rope is arranged, as in figs. 1 and 2, the workman places himself at the crank m, and, by turning, raises himself and the scaffold to the necessary height. A reverse operation, of course, lowers the scaffold to the ground. If but one workman is on the scaffold, he should operate alternately on the several cranks, so as to avoid raising one end faster than the other. By the arrangement shown in fig. 4, the scaffold may be raised or lowered from the top, bottom, or both simultaneously. The ratchet operates to prevent its going down again when once raised.

Having thus described my invention, what I claim as new, and desire to secure by Letters Patent, is—

The construction and arrangement of the frame B B, diagonal braces C C, plates D D, rollers d d, together with the sliding beams E E, thimbles e e, sheaves f g e k, cord a, gearing h, pawl n, ratchet o, cranks m x, and metallic shoes w w, or their equivalents, when in combination, substantially as and for the purposes specified.

A. S. KINNEAR.
